(57) **CLAIM**

The ornamental design for a worklight, as shown and described.

DESCRIPTION

FIG. 1 is a front perspective view of the worklight according to the present design;

FIG. 2 is a front view of the worklight as shown in FIG. 1; FIG. 3 is a back view of the worklight as shown in FIG. 1; FIG. 4 is a right side view of the worklight as shown in FIG. 1;

FIG. 5 is a left side view of the worklight as shown in FIG. 1;

FIG. 6 is a top bottom view of the worklight as shown in FIG. 1; and,

FIG. 7 is a bottom view of the worklight as shown in FIG. 1.

The broken lines shown in FIGS. 1-7 are to show portions of the worklight which form no part of the claimed design.

1 Claim, 6 Drawing Sheets
